SETTING APPARATUS FOR TEXTILE FABRICS

Henry Richter, Kankakee, Ill., assignor to Paramount Textile Machinery Co., Kankakee, Ill., a corporation of Illinois

Application June 21, 1946, Serial No. 678,231

21 Claims. (Cl. 223—76)

1

This invention relates to improvements in setting apparatus for textile fabrics and its purpose is to provide means for setting and shaping stockings and other fabrics formed by knitting linear condensation polyamide fibres such as those known by the name of nylon. The present invention is adapted to perform a cycle of operations somewhat similar to that performed by the horizontal type of apparatus described and claimed in my copending application Serial No. 581,210, filed March 6, 1945, now abandoned, but by the use of apparatus which is much more simple and capable of being manufactured at a much lesser cost.

Shaped textile articles formed from nylon yarn, such as hosiery, are commonly subjected to a so-called presetting operation on forms of the required shapes in the presence of saturated steam for the purpose of reducing the resiliency of the knitted loops and removing the natural wrinkles of the loose fabric, thereby causing the articles to retain the shapes of the forms during subsequent washing and use. The hosiery or other articles may be either dyed or of natural color when subjected to this presetting treatment which is carried on at a high temperature, preferably of from 240° Fahrenheit to 260° Fahrenheit, for a limited period and at a pressure above that of the atmosphere, thus necessitating the use of a closed chamber in which the articles are contained during the operation.

The principal object of the present invention is to provide apparatus of the type referred to comprising a vertical retort having an upright door which is held in closed position by its internal steam pressure during treatment and which carries on its opposite sides two sets of forms for the fabric articles so that one set of forms carrying hosiery or other articles may be on the inside of the door within the retort for treatment at the same time that the preboarding operations are being carried on outside of the retort on the other set of forms. Another object of the invention is to provide setting apparatus comprising a door having two sets of forms located on opposite sides thereof for supporting articles to be treated, said door being mounted for rotation about a vertical axis which is bodily movable with respect to the door opening so that by a combination of rotary and linear movements the door may be reversed in its position to permit locating the sets of forms alternately within the retort. A further object is to provide means for operating the door and for securing it in its closed position independently of the steam pressure within the retort. Still an-

other object is to provide a fabric setting retort having a reversible form carrying door of the type referred to wherein means are provided for limiting the temperature rise of the side of the door which is exposed to the steam in the retort and also means for cooling the region adjacent the outer side of the door where the preboarding operation is carried on. A further object is to provide fabric setting apparatus comprising a retort and a movable door therefor in combination with an automatic system for controlling the cycle of operation of the apparatus, including means actuated by the movement of the door to its closed position for initiating a sequence of operations during which the steam is admitted to the retort for a predetermined interval, a steam outlet valve is then opened, and the steam then exhausted from the retort in readiness for the opening of the door. Other objects relate to various features of construction and arrangement of the apparatus which will appear more fully hereinafter.

The nature of the invention will be understood from the following specification taken with the accompanying drawings in which one embodiment thereof is illustrated. In the drawings,

Fig. 1 shows a perspective view of the setting apparatus with the door of the retort in its closed position;

Fig. 2 shows a vertical section on the line 2—2 of Fig. 1;

Fig. 3 shows a vertical section on the line 3—3 of Fig. 2;

Fig. 4 is a perspective view of a portion of the front of the retort showing one of the door operating handles and latches and the switch actuated by the door for initiating the treating cycle;

Fig. 5 shows a horizontal section on the line 5—5 of Fig. 1;

Fig. 6 shows a horizontal section on the line 6—6 of Fig. 1;

Fig. 7 shows a horizontal section on the line 7—7 of Fig. 3, showing by full lines the door in its closed position and by dotted lines the door

when it has been opened but before it has been reversed by turning it about its own axis, the preboarding forms being omitted;

Fig. 8 shows a side elevation of one of the solenoid operated valves for controlling the flow of steam;

Fig. 9 is a horizontal section like that of Fig. 7 showing by full lines the position of the door after it has moved further inward from the position illustrated by dotted lines in Fig. 7 and, by dotted lines, the position of the door after it has

been partially reversed by turning about its own axis, the preboarding forms being omitted;

Fig. 10 shows, on a reduced scale, a top plan view of the retort and of the hydraulic connections and controlling devices for controlling the flow of steam to and from the retort;

Fig. 11 shows an enlarged vertical section through the outer portion of the cabinet which is shown attached to the right-hand portion of the retort in Fig. 1, illustrating the controlling and timing devices of the electric circuit by which the cycle of treating operations is controlled; and

Fig. 12 shows a schematic diagram of the electric circuit by which the cycle of operations is controlled.

As illustrated in the drawings, the invention comprises a retort 15 which is generally upright in form as shown in Figs. 1, 2 and 3 and curved in horizontal cross section in its rear part with a flat vertical front face, as illustrated in Figs. 5, 6, 7 and 9. This retort has a hollow base 16 adapted to rest upon a floor 11 or other support and this base has mounted thereon a bottom plate 18 upon which are mounted the inner shell 19 and the outer shell 20 of the rear and side portions of the retort walls. The inner shell 19 is formed of comparatively heavy metal and the two shells are spaced apart by transverse division members 21 which are united to the shells at their edges. The spaces between the shells and between the division members are filled with heat insulating material 22. The upper end of the chamber 24 of the retort is closed by an inner top wall 25 and the upper end of the outer shell 20 is closed by an outer top wall 26. The outer shell 19 is preferably welded to the bottom plate 18 and to the top wall 25. The front wall 27 of the retort is formed as a heavy metal plate which is bolted or otherwise secured to the adjacent division walls 21 from which it is separated by gaskets 28. At the left-hand side of the retort, as viewed in Figs. 1, 5, 6, 7 and 9, the outer shell 20 is extended over the edge of the front plate 27 and inwardly across the face of that plate as shown at 20^a and the extremity of this edge portion is bent inwardly at right angles to the plate 27 as shown at 20^b with its edge transversely bent and secured to the plate 27, thus forming an air chamber 29 which serves as a heat insulator for this portion of the front wall of the retort. Similarly, at the right-hand side of the front wall of the retort, as shown in Figs. 1, 5, 6, 7 and 9, the outer shell 20 is projected forwardly beyond the wall 27 and is then bent transversely inward as shown at 20^c and thence inwardly as shown at 20^d, with its edge united to the plate 27, thus forming another vertical air chamber 30 along the right-hand forward edge of the front wall of the retort.

High temperature steam is introduced under pressure into the chamber 24 of the retort through an inlet pipe 31 which leads through the bottom wall 18, as shown in Fig. 3, this pipe opening beneath a false bottom or distributor plate 32 which is spaced upwardly from the bottom wall 18 by supporting brackets 34 and which has its marginal edges spaced from the adjacent inner walls of the chamber 24 so that the steam introduced through the pipe 31 is distributed by the plate 32 and caused to pass upwardly around all of the edges of this plate to effect thereby a more even distribution of the steam throughout the treating chamber. A drainage pipe 35 for the condensate which collects within the chamber 24 leads outwardly through the bottom wall 18 which

is sloped downwardly to this outlet, as illustrated in Fig. 3. A steam outlet pipe 36 leads through the top walls 25 and 26, as shown in Fig. 2, and an exhaust pipe 37, connected to the suction apparatus hereinafter described, also communicates with the upper part of the chamber 24 through the rear portions of the inner and outer shells, as shown in Fig. 2. The upper part of the chamber 24 also has an outlet through a pipe 38, shown in Fig. 3, which leads through the inner and outer shells and is connected to pressure relief valves 39 and a pressure gauge 40, shown in Fig. 1. A baffle plate 41 extends inwardly from a point just below the mouth of the pipe 38 with its inner end connected to a bracket 42 carried by the top wall 25 so that hot condensate collecting at the top of the chamber 24 will not drop onto the hands of the operator during the process of reversing the position of the door. A thermometer 44 is also connected to the upper part of the chamber 24 at the side opposite the pipe 38, as illustrated in Fig. 1, to indicate the steam temperature therein.

The front plate 27 of the retort is provided with an upright rectangular door opening 27^a which is adapted to be closed by a door 45 having the pivotal and bodily movements heretofore referred to. This door has mounted on the inner and outer sides thereof two series of upright boarding forms 46 which in this case are shown as forms for use in the setting of ladies' hosiery. The forms are adapted to be tilted away from the body of the door when they are on the outside of the retort, as shown at 46^a in Fig. 2, to permit the removal of hosiery thereon and the replacement of hosiery which is to be treated, while, in the meantime, the other forms 46 on the inside of the retort are subjected to the wet steam treatment heretofore mentioned. These forms 46 are mounted on the door 45 for pivotal movement outwardly therefrom in much the same manner as that illustrated in connection with the forms shown in the United States patent to Leslie H. Oswald et al., No. 2,351,063, dated June 13, 1944. For this purpose, supporting frames 48 are secured to the opposite faces of the door adjacent the bottom thereof, as shown in Figs. 1 and 3, there being two such frames on each side of the door. The frames of each pair carry two transverse rods 49 and 50, the former of which is adapted to be engaged by the bifurcated lower extremities of the brackets 51 upon which the forms 46 are mounted. The brackets 51 are spaced apart by collars 52 on the rod 49 and, when they are swung outwardly as shown at 46^a in Fig. 2, their outward movement is limited by the engagement with the rod 50 of hook-shaped rearwardly extending extremities 51^a formed on these brackets. The frames 48 of each pair are also connected at their upper margins by a transverse rod or bolt 54 and at each side of each series of forms 46 a heat retaining plate 55 is mounted on the frame 48 to extend upwardly therefrom at the sides of the endmost forms 46 of the series. These plates have the function of maintaining the temperatures of the endmost forms 46 which otherwise tend to drop below the temperatures of the intervening forms of the series when the forms are in the retort, thus insuring a uniform degree of digress of all of the articles of hosiery on a set of forms when that set is moved to the outside of the retort. The frames 48 of each pair also carry horizontally extending guard rails 56 which project outwardly opposite the brackets 51 of the adjacent forms 46 for the purpose of di-

recting the movement of the door during its rotation, as hereinafter described.

As shown particularly in Figs. 2, 3 and 6, the door 45 consists of a solid rectangular sheet of heavy steel boiler plate of substantial thickness, for example 1½ inches thick or more, and this plate is provided along its marginal edges on both sides thereof with rubber sealing flanges 57 which are adapted to engage the edges of the plate 27 around the door opening 27^a to form a fluid-tight seal when the door is closed, this seal being rendered more effective by the steam within the chamber 27 of the retort. The sealing members 57 are secured in place by metal strips 58 which are secured to the edges of the door proper and by other strips 59 which are secured to the faces of the door. The door also comprises two thin stainless steel plates 60 which are secured to the opposite faces thereof and which cover the entire area of the door inside the metal strips 59. These sheets 60 are loosely attached to the door so that they form air spaces on their inner sides adjacent the surfaces of the heavy metal plate of which the body of the door is formed, thus limiting the temperature rise of this heavy metal plate on the side thereof which is exposed to the steam in the chamber 24 so that when the door is reversed and the hot side of the door is exposed on the outside of the retort, the temperature of the door will be less objectionable to the operator who is changing the hosiery on the forms 46 on the outside of the door. On each side of the door, adjacent its upper extremity, there is mounted a hollow shell or receptacle 61 which is adapted to catch the condensate which collects on the upper wall of the chamber 24 so that this condensate will not drop onto the hosiery carried by the forms which are within the chamber and cause injury to the hosiery or other articles which would otherwise occur due to the dropping of this condensate on them, particularly if they are dyed.

The door 45 is supported by two arms 64 and 65 which are secured upon a vertical shaft 66 mounted within the chamber 24 at the side of the door opening. The door is provided at its lower end with an axially located stub shaft 67 which is fixed in a hub or socket 68 welded or otherwise secured to the lower edge of the door. The stub shaft engages a bearing formed in the extremity 64^a of the arm 64 and an anti-friction thrust bearing 69 is interposed between the extremity 64^a and the hub 68 to carry the weight of the door and the objects mounted on the door. At its upper end the door is provided with another axially located shaft 70 fixed in a hub or socket 71 which is welded or otherwise secured to the upper edge of the door. The stub shaft 70 engages a bearing in the hub portion 65^a formed at the end of the arm 65. Both of the arms 64 and 65 are secured on the shaft 66 which is arranged with its lower end extending into a hub or socket member 72 secured to the bottom wall 18 of the retort. An anti-thrust bearing 74 is interposed between the socket or bearing member 72 and the hub portion 64^b which is formed on the inner end of the arm 64 for engagement by the shaft 66 so that the weight of the arm 64 and the door is transmitted to the thrust bearing 74. Between the two arms 64 and 65, the shaft 66 is supported laterally by roller bearing units 76 in which the shaft is journaled and which are secured to bearing brackets 77, also welded or otherwise secured to the portion of the inner shell 20. In this way, the door 45 is supported so that it is freely mov-

able about its own axis of rotation formed by the stub shafts or trunnions 67 and 70, and at the same time the door is movable bodily toward and from its closed position by the movement of the arms 64 and 65 and the corresponding rotation of the shaft 66 in its bearings.

The movements of the door which have just been referred to are effected manually after the supply of steam has been shut off and the steam 10 in the chamber 24 has been exhausted. For convenience in performing this manual operation and also to permit the door to be latched in its closed position independently of the steam pressure on the inside of the retort, so that the attendant can work on the forms on the outside of the door without pushing the door inwardly, even though the steam pressure is relieved, the door is provided with combination handles and latch devices which are illustrated particularly in Figs. 20 1, 2 and 4. Each of these devices comprises a handle 80 carried by an arm 80^a which is formed integrally with or welded to a plate 81 secured to the face of the door 45 by studs 82. Each plate 81 carries an outwardly extending bar 84 upon 25 which a latch member 85 is pivoted by means of a pin 86. Each latch member has a depending shoulder 85^a adapted to drop down on the forward side of a bar 87 which is secured to the front plate 27 of the retort at the side of the door opening and which projects outwardly beyond the edge of the door opening as shown in Fig. 4. The latch member will drop by gravity to engage the bar 87 when the door is fully closed and when it is desired to release the door to 30 permit its inward movement, the latch members 85 are elevated by means of links 88 which are connected to pins 89 extending from the latch members through slots 84^a which are formed in the bars 84. The links 88 are operated by levers 40 or triggers 89 pivoted at 90 on the arms 80^a. Portions of these triggers 89 are located in proximity to the upper ends of the handles 80 for engagement by the thumbs of the operator so that both latch members may be released simultaneously and the door may then be swung 45 inwardly by pushing on the handles and caused to partake of the bodily movement and the rotary movement heretofore described.

For the purpose of guiding the door 45 in its movements, there is provided a guide member 91 formed from a flat bar which is attached to the plate 27 at the bottom of the door opening 27^a with its ends extending parallel to the plane of the plate 27 to which they are attached. Adjacent the left-hand side of the door opening as viewed in Figs. 1, 3, 7 and 9, the guide member 91 is bent to form an outwardly extending loop 91^a and at the right-hand inner margin of this loop, the bar of the guide member is reversely bent to 50 form a curved portion 91^b which is convexed outwardly and extends between the part 91^a and the end portion 91^c which is attached to the plate 27. At the other side of the loop portion 91^a, the bar is curved laterally as shown at 91^d so that a roller 92 may be directed into engagement with the loop portion when the door is moved forwardly. This guide member is adapted to be engaged by either one of two rollers 92 each of which is mounted at the outer end of an arm 94. One of these arms 60 94 is secured to each face of the door 45 in such a position that one of these arms will project outwardly through the left-hand lower portion of the door opening, whichever face of the door is directed outwardly. As the door 45 is moved forwardly from the position shown by dotted lines 65 70 75

in Fig. 7, one of the rollers 92 passes into engagement with the loop portion 91^a of the guide member so that the door is guided and held against rotation about its own axis as it moves from the position shown by dotted lines in Fig. 7 to the position shown by full lines in that figure. When the door is pushed inward slightly further than the position illustrated by dotted lines in Fig. 7, the forward roller 92 passes out of engagement with the loop portion 91^a of the guide member and is then free to travel along the curved portion 91^b of this guide member as the reversal of the door by rotation about its own axis is begun, as illustrated by full lines in Fig. 9.

In addition to the foregoing guiding means located at the bottom of the door opening, a roller 95 is mounted in a bracket 96 at the left-hand side of the door opening, as viewed in Figs. 7 and 9, for engagement with the guard members 56 which have previously been described as being attached to opposite sides of the door 45 to extend on the outer sides of the brackets 51 upon which the forms 46 are mounted. The outer curved portions 56^a of these guard members are concentric with the axis of rotation of the door 45 about its own axis and when this rotation is imparted to the door, one or the other of these guard members 56 engages the roller 95 so that the door is freely rotatable and during this rotation the forms are kept out of contact with the inner walls of the retort chamber.

Other guarding means are provided at the top of the retort by a substantially semi-circular guide member 97 which is attached to brackets 98 carried by the inner top plate 25 of the retort and which occupies a position in a horizontal plane slightly above the upper edge of the door 45. The door is provided adjacent the extremities of its top edge with two rollers 99, mounted on trunnions 100, which are adapted to engage the guide member 97 for guiding the door while its position is being reversed within the retort. After the door has been released in the position shown by full lines in Fig. 7 and has been pushed inwardly to a position somewhat beyond that illustrated by dotted lines in that figure, the door is then rotated about its axis and during this rotation one or the other of the rollers 99 travels on the outer convex side of the guide member 97 as shown in Fig. 9 where the door in the position illustrated by full lines is shown as having one of the rollers 99 engaging an intermediate portion of this guide member. After that roller has passed out of engagement with the guide member 97 as shown by dotted lines at the rear of Fig. 9, the rotation of the door about its own axis may be completed with the other roller 99 then passing on the outside of the guide member 97 and, when the door has been completely reversed in its position, it may then be swung forwardly to the position shown by dotted lines in Fig. 7 where one of the rollers 92, carried by an arm 94, is just engaging the outwardly projecting loop portion 91^a of the guide member 91. The operator then pulls the door forwardly by engaging the handles 80 which are on the outside of the door until the latch members 85 engage the bars 87.

In order to reduce the temperature of the atmosphere in the space occupied by the operator while removing the treated articles from the forms and replacing them with untreated articles, means are provided for circulating cool air toward the operator's position. This is effected by a sheet metal air chamber 101 which extends along the right-hand portion of the bottom of the re-

tort beneath the door opening and which extends beyond the right-hand side of the retort as shown in Figs. 1 and 5. This air chamber 101 has an inlet opening 101^a opening rearwardly at the side of the retort and an air circulating motor 102 is mounted on the side of the retort rearwardly of this opening with its air circulating fan 102^a mounted within the extension of the air chamber inside of the inlet opening 101^a. When the apparatus is in operation, this motor 102 is actuated to draw air into the chamber 101 and to discharge it through a slot 101^b which is formed in the upper forward part of the chamber as shown in Fig. 1 and which directs the cool air upwardly toward the operator's position.

The means for introducing steam into the chamber 24 of the retort and for exhausting it therefrom is illustrated somewhat diagrammatically in Fig. 10. As there shown, the previously mentioned steam inlet pipe 31, also shown in Fig. 3, leads from a steam supply pipe 104 through a shutoff valve 105, a strainer 106, a pressure regulator 107, and a solenoid operated valve 108 to the place where it opens through the bottom plate 18 of the retort as previously described to discharge steam into the chamber 24 of the retort at the proper times during the cycles of operation of the apparatus. The pressure regulator 107 is provided with the usual lever 107^a on which adjustable weights 107^b are mounted for regulating the pressure of the steam within the chamber of the retort so that it will have the desired value, usually between 15 and 35 pounds per square inch. The drain pipe 35, also shown in Fig. 3, leads from the center of the bottom plate 18 of the retort, as previously described, and communicates with a larger pipe 110 which extends to the sewer or other place of drainage disposal.

The outlet pipe 36, which leads through the top of the retort as shown in Figs. 1 and 2, has a check valve 111 connected therein and it is provided for allowing the escape of air during the period that steam is being introduced into the chamber 24 of the retort. This check valve 111 is thermostatically controlled and automatically closes when the air has been discharged and the space within the retort is occupied entirely by steam.

The exhaust pipe 37, illustrated in Fig. 2, is shown in Fig. 10 as leading from the rear upper part of the retort through a solenoid operated valve 112 which is controlled electrically in the manner hereinafter described, and the pipe 37 then leads through an elbow-like siphon member 114 from which it extends horizontally for discharging the steam exhausted from the retort after each training operation. For the purpose of creating suction for withdrawing the steam, the siphon member 114 has connected horizontally therein a small steam jet pipe 115 which leads through a solenoid operated valve 116 and a strainer 117 from an elbow 118 by which a connection is established between this smaller steam pipe and the steam supply pipe 31 through which live steam is introduced into the retort. It will be noted that the elbow 118 is connected in the pipe 31 between the strainer 106 and the pressure regulator 107 so that steam is supplied to the siphon member 114 at boiler pressure and not at the pressure which is maintained in the retort. The effect of the discharging steam in the pipe 37 is to create a suction in the siphon member 114 and in the portion of the pipe 37 between the retort and the member 114 so that the

steam in the chamber of the retort is thereby exhausted when the solenoid operated exhaust valve 112 is open.

The solenoid operated valves 108, 112 and 116 may be of the same general construction, differing from each other only with respect to the fact of being normally open or normally closed. These valves may be of a type well known in the art, such as the valve manufactured and sold by Automatic Switch Company of New York, New York. In Fig. 8 the solenoid operated valve 108 is shown in side elevation and is illustrated as comprising a casing 108^a having mounted therein a solenoid surrounding a magnetizable plunger 108^b which is connected at its lower end to a lever 108^c pivoted at 108^d on the valve frame. This valve is normally closed by the action of a coil spring 108^e but when the solenoid is energized, it is opened against the tension of the spring in response to the upward movement of the lever 108^c, thereby admitting steam to the retort. The solenoid operated valve 112 is normally open but is adapted to be closed at the same time that the valve 108 is opened, thereby closing the exhaust channel during the time that steam is being admitted. The solenoid operated valve 116 in the siphon line is also normally closed but, at the conclusion of the heat treating operation, this valve is opened at the time that the solenoid operated valve 112 is opened by the deenergization of its solenoid so that the opening of the valve 116 is effected to create a suction in the exhaust line when the valve 112 is opened.

The electrical system for controlling the solenoid operated valves 108, 112 and 116 and other parts of the apparatus are illustrated particularly in Figs. 11 and 12. In Fig. 11 there is shown a vertical section through the outer portion of a control cabinet 120 which is mounted on the upper right-hand portion of the outer wall of the retort, as illustrated in Fig. 1. The supply conductors 121, connected with a source of alternating current, lead through a fuse block 122 to a manually operated switch 124 mounted on the inside of the front end wall of the cabinet and having an operating member 124^a projecting through an opening in the cabinet for engagement by the fingers of the operator who closes this switch preliminary to putting the apparatus in operation. In the lower left-hand part of the cabinet there is mounted a casing 125 containing two clock-driven timers 126 and 127. The timer 126 is adapted to be adjusted to control the period during which steam is admitted to the retort after the temperature within the retort has risen to a predetermined degree following the initial introduction of steam into the chamber 24 and it bears on its face a series of graduations 126^a adjacent which a pointer 126^b is adapted to move. This pointer may be set through the operation of a handle 126^c to cause the steam to be introduced through a predetermined interval after the predetermined temperature has been attained and, at the end of that period, the clock mechanism operates this timer to control the circuit for shutting off the flow of steam and, at the conclusion of the cycle, the pointer 126^b is restored to its zero position in readiness for another cycle of operations. The other timer 127 is provided for the purpose of regulating the period during which steam is exhausted from the retort following each heat treating operation. This timer also has a series of graduations 127^a adjacent which a pointer 127^b is adapted to move and this pointer may be adjusted to a predetermined position by

a handle 127^c for setting the duration of the exhaust period. At the end of the cycle, the pointer 127^b is again restored to its set position by the action of the internal mechanism of the timer, in readiness for another cycle of operations. There is mounted in the casing 125 a manually operated switch 128 which is connected in the circuit of the previously described fan motor 102 by which air is caused to be directed toward the operator's position while the apparatus is in operation. The cabinet 120 also contains a terminal block 129 having thereon terminal posts for convenience in making electrical connections between the different parts of the apparatus and in the central portion of the cabinet there are mounted two electromagnetic switches 130 and 131, the operation of which is controlled by the timers in the manner hereinafter described. In the lower right-hand corner of the cabinet 120 and connected in the electric circuit is a heat control switch 132 which has a thermostatic portion extending into the chamber of the retort and which may be adjusted for a predetermined setting by a rotary adjusting member 132^a bearing graduations which may be positioned with respect to an index mark to indicate and determine the temperature at which the circuit will be made effective to operate the timer 126 for controlling the duration of the further flow of steam into the retort.

The circuit connections of the various devices shown in Figs. 10 and 11 are illustrated diagrammatically in Fig. 12. This circuit includes a door operated switch 134 which is illustrated in Fig. 4 as being mounted at the right-hand side of the door opening on the front plate 27 of the retort. The door 45 carries two actuating pins 135 mounted on opposite edges of the door so that when the door is in either fully closed position, one of these pins will engage the operating member of the switch 134 and close the circuit, thus initiating the cycle of operations hereinafter described. The circuit also includes a door operated switch 136 which is mounted on the front plate 27 of the retort below the switch 134, as shown in Fig. 4, for the purpose of closing the circuit of the fan motor 102 when the door 45 is fully closed and under steam pressure. This switch has an actuating member which is operated by a pin 137 projecting from the face of the door 45. One of these pins 137 is provided on each side of the door so that when the door is reversed in position a pin will be in the proper location to engage the actuating member 136^a and thereby close the switch 136. The adjustment of the switch 136 is preferably such that when the steam pressure in the retort is released and the door 45 moves in slightly, due to the expansion of the rubber strips 57 along the edges of the door, the switch 136 will be opened thereby discontinuing the operation of the fan motor 102.

When the door 45 is closed by the operator, the switch 134 is thereby closed and this completes the circuit from one of the supply conductors 121 through the conductor 138, the switch 134, the conductor 139 and the conductor 140 to the switch arm 141 of the timer 126. This arm is then in its upper position engaging its upper contact which leads through the conductor 142 and the conductor 144 to the solenoid 130^a of the electromagnetic switch 130. The other terminal of this solenoid is connected through the conductor 146 and the conductor 147 to the other supply conductor 121. The circuit is thus completed to energize the electromagnetic switch 130 with the result that the double pole contact

member 130^b thereof is actuated to connect the contacts 148 also the contacts 149. The closing of these contacts provides a direct connection from the supply conductors 121 through the conductors 147 and 150 and the conductors 151 and 152, respectively, to the terminals of the solenoid operated valves 108 and 112 which are connected in parallel, as illustrated diagrammatically in the upper part of Fig. 12. As these solenoid operated valves are simultaneously energized, steam is admitted through the supply pipe 31 and the open valve 108 to the bottom of the chamber 24 of the retort and the steam then flows into this chamber while, at the same time, the air in the chamber flows out through the vent pipe 36 until the temperature within the chamber is sufficient to close the automatic check valve 111. The steam will continue to flow into the chamber and the temperature will rise until, at a predetermined degree, the thermostatic heat control valve 132 is automatically closed by the action of its thermostatic element. The closing of this switch 132 establishes a connection from one supply conductor 121 through the conductor 147, the upper contact 148, the conductor 154, the switch 132, the conductor 155, the motor 156 of the timer 126, the conductor 157, the conductor 158, the switch arm 141, the conductor 140, the conductor 139, the switch 134 and the conductor 138 to the other supply conductor 121. The motor 156 of the timer 126 is thus started in operation and the timer, controlled by its clock mechanism, measures the interval during which the steam will continue to flow into the retort, this interval being determined by the initial setting of the pointer 126^b of the timer. As the motor 156 continues to operate, the pointer 126^b will move steadily toward its zero position and when it reaches that position the switch 141 of the timer automatically drops into engagement with its lower contact and the motor 156 is stopped, thereby terminating the heat treating period.

The engagement of the switch arm 141 of the timer 126 with its lower contacts establishes a circuit from the conductor 138, switch 134, conductor 139, conductor 140 and switch arm 141 through the conductor 160 which leads to one terminal of the solenoid 131^a of the electromagnetic switch 131. The energization of this solenoid actuates the double pole switch member 131^b of this switch to connect the contacts 161 thereby establishing a connection from the previously mentioned conductor 155 through the conductor 162, contacts 161 and conductor 164 to the conductor 147 which is connected to the upper supply conductor 121. There is thus automatically established a shunt connection around the thermostatic heat control valve 132 so that this part of the circuit is maintained even though the switch 132 may open with a fall in temperature during the exhaust period.

At the same time that the shunt connection just referred to is established, the engagement of the switch arm 141 of the timer 126 with its lower contact also establishes a connection through the conductor 160 and the conductor 165 to the movable switch arm 166 of the siphon timer 127. This switch arm is then in its upper position as shown in Fig. 12 so that a connection is established from its upper contact through the conductors 167, 168 and 169, to one terminal of the solenoid operated valve 116 which controls the siphon line. The other terminal of this valve 116 is connected through a conductor 170 to the

other supply conductor 121. The siphon valve 116 is thereby opened and steam drawn from the supply line 31 flows through the siphon pipe 115 and creates a suction which causes steam to be withdrawn through the exhaust line 37, the solenoid operated exhaust valve 112 having been opened at the same time that the inlet valve 108 was closed by the opening of its circuit upon the dropping of the switch arm 141.

At the same time that the siphon valve 116 is opened, by the dropping of the switch arm 141, the circuit is closed through the motor 171 of the siphon timer 127, this circuit leading from the conductor 165 through the reset relay coil 172 and the conductor 174 through the motor 171, to the conductor 168. Upon establishing the circuit of the motor 171, this motor begins to operate under the control of the clock mechanism of the timer with the result that the pointer 127^b of this timer moves steadily toward its zero position from its initial setting which determines the duration of the exhaust period. At the end of that period, when all of the steam has been withdrawn from the chamber 24 of the retort, the clock mechanism of the timer causes the switch arm 166 to drop to its lower contact thereby opening the circuit of the solenoid operated siphon valve 116 which is then actuated by its spring to move to its closed position. Although a circuit is still established through the motor 171 of the timer 127, the high resistance of the winding 172 of the relay will prevent the operation of the motor when the switch arm 166 is in its open position. The exhaust period is thus automatically terminated and the steam having been removed from the interior of the retort, the operator who has placed a new set of hosiery on the forms on the outside of the door may open the door and prepare to reverse the position of the door in order to bring to the outer side thereof the forms carrying the hosiery which have just been treated in the chamber. When the exhaust period has ended, that fact will be indicated to the operator by the absence of any noise or suction within the chamber 24 as well as by the slight inward movement of the door in response to the release of the steam pressure on its inner side and the latches 85 may then be released by manipulating the triggers 89 so that the door may be pushed inwardly to allow the door operated switch 134 to open. When this switch is opened, the switch arms 141 and 166 are automatically restored to their normal upper positions, as shown in Fig. 12, by the action of the reset relays 172 and 173, in readiness for another cycle of operations. When the solenoids 130^a and 131^a of the electromagnetic switches 130 and 131, respectively, are deenergized by the opening of their circuits, the switch contact members 130^b and 131^b are automatically moved to their open positions by spring pressure or the like.

During the heat treating period which occupies the first part of the cycle of operations just described, the door operated switch 136 is closed, thereby establishing a connection from one supply conductor 121 through conductors 138 and 175 to one terminal of the fan motor 102 and thence from the other terminal of that fan motor through the conductor 176, the conductor 177, the door operated switch 136, the conductor 178, the manually operated switch 128, and the conductors 154 and 147 to the other line conductor 121. The manual switch having been closed at the beginning of the operations, the closing of the door thus establishes the circuit of the fan motor 102 which will continue to operate throughout the

heat treating period, thus causing cool air to be discharged in the direction of the position occupied by the attendant in front of the retort. Following the conclusion of the heat treating period and as soon as the exhaust portion of the cycle has relieved the steam pressure within the chamber sufficiently to permit the door 46 to move inwardly to a slight extent due to the expansion of the rubber strips 57, the switch 136 is automatically opened so that the fan motor 102 does not operate during the remainder of the cycle.

Although one form of the invention has been shown and described by way of illustration, it will be understood that it may be constructed in various other embodiments which come within the scope of the appended claims.

I claim:

1. The combination in setting apparatus of the class described, of a retort having a door opening, a reversible door located at all times within the retort for closing said opening with either face of the door directed outwardly, and forms mounted on both faces of said door for supporting textile articles.

2. The combination in setting apparatus of the class described, of a retort having a door opening, a door for closing said opening, means for mounting said door to permit bodily movement and pivotal movement thereof within the retort whereby said door may be reversed in position to cause either face thereof to be directed outwardly, and forms mounted on both sides of said door for supporting textile articles.

3. The combination in setting apparatus of the class described, of a retort having a door opening, an inwardly movable door for closing said opening, means for mounting said door to permit movement thereof bodily inward from said opening and to permit rotation thereof about a vertical axis, and forms mounted on both faces of said door for supporting textile articles.

4. The combination in setting apparatus of the class described, of a retort having a door opening and a door seat around said opening on the inside of the retort, and means for mounting said door to allow it to be reversed within said retort to cause either door face to engage said seat.

5. The combination in setting apparatus of the class described, of a retort having a door opening and a door seat around said opening on the inside of the retort, means for mounting said door to allow it to be reversed within said retort to cause either door face to engage said seat, and forms mounted on both faces of said door for supporting textile articles.

6. The combination in setting apparatus of the class described, of a retort having a door opening, a reversible door for closing said opening with either face of the door directed outwardly, forms mounted on both faces of said door for supporting textile articles, and means for mounting said forms to permit independent movements thereof with respect to said door.

7. The combination in setting apparatus of the class described, of an upright retort having a vertical door opening and a door seat on its inner side around said opening, a door located within said retort for engaging said seat to close said opening, a support for said door mounted to swing about a vertical axis, and means for permitting rotation of said door on said support.

8. The combination in setting apparatus of the class described, of an upright retort having a vertical door opening and a door seat on its inner side around said opening, a door located within

5 said retort for engaging said seat to close said opening, a support for said door mounted to swing about a vertical axis, means for permitting rotation of said door on said support, and forms mounted on both faces of said door for supporting textile articles.

9. The combination in setting apparatus of the class described, of a retort having a door opening and a door seat on its inner side around said opening, a door movable within said retort against said seat, an upright shaft journalled in bearings within said retort, and arms fixed on said shaft and pivotally connected to the upper and lower ends of said door.

10 15 The combination in setting apparatus of the class described, of a retort having a door opening and a door seat on its inner side around said opening, a door movable within said retort against said seat, an upright shaft journalled in bearings within said retort, arms fixed on said shaft and pivotally connected to the upper and lower ends of said door, and forms mounted on both faces of said door for supporting textile articles.

20 25 The combination in setting apparatus of the class described, of a retort having a door opening and a door seat on its inner side around said opening, a door movable within said retort against said seat, means for admitting steam to said retort, the pressure of said steam being adapted to force said door against said seat, and means for securing said door in closed position independently of said steam pressure.

30 35 The combination in setting apparatus of the class described, of a retort having a door opening and a door seat on its inner side around said opening, a door movable within said retort against said seat, forms mounted on both faces of said door for supporting textile articles, means for mounting said door to permit either face thereof to be presented outwardly, means for admitting steam to said retort, the pressure of said steam being adapted to hold said door against said seat, and means including latches mounted on both faces of said door for securing said door in closed position independently of said steam pressure.

40 45 The combination in setting apparatus of the class described, of a retort having a door opening and a door seat on its inner side around said opening, a door for closing said opening, means for mounting said door for reversal thereof whereby either face of said door may be presented outwardly at said opening, forms mounted on both faces of said door for supporting textile articles, and sealing means on both faces of said door for engaging said seat.

50 55 The combination in setting apparatus of the class described, of a retort having a door opening and a door seat on its inner side around said opening, a door for closing said opening, means for mounting said door for reversal thereof whereby either face of said door may be presented outwardly at said opening, forms mounted on both faces of said door for supporting textile articles, means forming an air chamber outside of said retort adjacent said door, said chamber having an opening directed toward the area in front of said door, and means for discharging air through said opening.

60 65 The combination in setting apparatus of the class described, of a retort having a door opening and a door seat on its inner side around said opening, a door for closing said opening, means for mounting said door for reversal thereof

15

whereby either face of said door may be presented outwardly at said opening, forms mounted on both faces of said door for supporting textile articles, and thin metal plates mounted loosely on each face of said door behind said forms.

16. The combination in setting apparatus of the class described, of a retort having a door opening and a door seat on its inner side around said opening, a door movable against said seat to close said opening, means for reversing said door to cause either face thereof to engage said seat, forms mounted on said door for supporting textile articles within said retort, means for admitting steam to said retort, and means actuated by the movement of said door for controlling the flow of steam to said retort.

17. The combination in setting apparatus of the class described, of a retort having a door opening and a door seat on its inner side around said opening, a door movable against said seat to close said opening, means for reversing said door to cause either face thereof to engage said seat, forms mounted on said door for supporting textile articles within said retort, means for admitting steam to said retort, and means actuated by the movement of said door for controlling the flow of cool air to the space outside of said retort opposite said door.

18. The combination in setting apparatus of the class described, of a retort having a door opening and a door seat on its inner side around said opening, a door movable against said seat to close said opening, means for reversing said door to cause either face thereof to engage said seat, forms mounted on said door for supporting textile articles within said retort, means for admitting steam to said retort, means for exhausting steam from said retort, and means including an electric circuit having timing devices connected therein for controlling the duration of the steam admission and exhaust periods.

19. The combination in setting apparatus of the class described, of a retort having a door opening and a door seat on its inner side around said opening, a door movable against said seat to close said opening, means for reversing said door to cause either face thereof to engage said seat, forms mounted on said door for supporting tex-

16

tile articles within said retort, means for admitting steam to said retort, means for exhausting steam from said retort, means actuated by the closing of said door for causing steam to flow into said retort, and means actuated when the temperature in the retort reaches a predetermined degree for determining the duration thereafter of said flow of steam into said retort.

20. The combination in setting apparatus of the class described, of a retort having a door opening and a door seat on its inner side around said opening, a door movable against said seat to close said opening, means for reversing said door to cause either face thereof to engage said seat, forms mounted on said door for supporting textile articles within said retort, means for admitting steam to said retort, means for exhausting steam from said retort, means actuated by the closing of said door for causing steam to flow into said retort, means actuated when the temperature in the retort reaches a predetermined degree for determining the duration thereafter of said flow of steam into said retort, and means actuated upon the stoppage of the flow of steam to said retort for exhausting steam from said retort by said exhausting means.

21. The combination in setting apparatus of the class described, of an upright retort having a vertical door opening, a door located within said retort for closing said opening, means for mounting said door to permit bodily movement thereof and rotation thereof on a vertical axis within said retort whereby either face of the door may be presented outwardly when the door is closing said opening, and forms mounted on both faces of said door for supporting textile articles.

Certificate of Correction

Patent No. 2,451,978.

October 19, 1948.

HENRY RICHTER

It is hereby certified that errors appear in the printed specification of the above numbered patent requiring correction as follows:

Column 1, line 11, after "March 6, 1945," strike out "now abandoned,"; column 13, line 73, claim 8, for "reteort" read *retort*;

and that the said Letters Patent should be read with these corrections therein that the same may conform to the record of the case in the Patent Office.

Signed and sealed this 15th day of March, A. D. 1949.
